UNITED STATES PATENT OFFICE.

MYRON B. DURGA, OF CENTRALIA, WASHINGTON.

VALVE-GRINDING APPARATUS.

1,126,735.

Specification of Letters Patent.

Patented Feb. 2, 1915.

Application filed September 24, 1914. Serial No. 866,325.

To all whom it may concern:

Be it known that I, MYRON B. DURGA, a citizen of the United States, residing at Centralia, in the county of Lewis and State of Washington, have invented certain new and useful Improvements in Valve-Grinding Apparatus, of which the following is a specification.

My invention relates to improvements in apparatus for grinding the valves of an internal combustion engine.

An important object of the invention is to provide apparatus of the above mentioned character, which is simple in construction, inexpensive to manufacture, convenient in use, durable, and reliable in operation.

A further object of the invention is to provide apparatus of the above mentioned character which will effect a substantial saving in both time and labor, in accomplishing the work for which it is intended.

Other objects and advantages of the invention will be apparent during the course of the following description.

In the accompanying drawings, forming a part of this specification and in which like numerals are employed to designate like parts throughout the same, Figure 1 is a side elevation of apparatus embodying my invention, showing the same in use, Fig. 2 is a horizontal sectional view taken on line 2—2 of Fig. 1, Fig. 3 is an edge elevation of the same, and, Fig. 4 is a horizontal sectional view taken on line 4—4 of Fig. 1.

In the drawings, wherein for the purpose of illustration is shown a preferred embodiment of the invention, the numeral 10 designates a vertical post or support, adapted to be rigidly connected with the cylinder of the engine by any suitable means. This post is preferably formed square in cross-section. As illustrating a preferred means for attaching the post to the cylinder of the engine, I have shown the lower end thereof screw-threaded, at 11, for screw-threaded engagement within the spark-plug opening of the cylinder. However, any other suitable means may be employed to rigidly attach this post to the cylinder.

The numeral 11' (see Figs. 1 and 2) designates an adjustable supporting frame, as a whole, including an apertured block or

head 12 longitudinally or vertically adjustably mounted upon the post 10, and clamped thereto in adjustment in the desired vertical position, by a clamping bolt 13 or the like, as shown. Rigidly attached to the ends of the block or head 12 are spaced horizontal arms 14, having blocks or heads 15, horizontally or longitudinally adjustably mounted thereon, the same being clamped to the arms 14 in adjustment at the desired longitudinal position, by clamping bolts 16, or the like.

The numeral 17 designates driving means, as a whole, embodying a reciprocatory frame 17', formed of longitudinally movable rods 18, connected at their ends by depending or curved transverse rods 19, as shown. The rods 18 are mounted to reciprocate within transverse apertures 20, formed through the blocks 15. Secured to one transverse rod 19 is a handle 21, by means of which the frame 17' may be reciprocated. Connected with the end rods 18 and extending longitudinally of the frame 17' and below the same, is a flexible element 22, such as a cord, cable or the like. This flexible element is wound once about a vertical spool 23, having an axially extending opening, which is square in cross section.

The numeral 24 designates a preferably vertically arranged rotatable and longitudinally movable spindle or shaft, having cylindrical end portions 25, and an intermediate portion 26, formed square in cross-section to fit within the axial opening of the spool 23, whereby the spool or pulley is splined thereon.

The numeral 27 (Figs. 1 and 4) designates adjustable bearing supports, which are identical. Each of these bearing supports 27 comprises a block or head 28, apertured to receive the post 10 and to be longitudinally adjustably mounted thereon. By means of a clamping bolt 19' each head 28 may be locked to the post 10 in adjustment at the desired vertical position. Rigidly attached to the head 28 are spaced horizontal arms 30, upon which is longitudinally adjustably mounted a transverse bearing block 31, apertured to receive the arms 30, and adapted to be clamped thereto, by bolts 32 and the like. The bearing block 31 is apertured to receive the spindle 24 and

serves as guide means for the same, allowing the spindle to rotate and to be moved vertically up and down. The intermediate bearing block 31, receiving the square portion 26 of the spindle, has its opening formed sufficiently large whereby it does not interfere with the rotation of the spindle, and serves as a support for the spool 23 or pulley with which it has slidably engagement, as shown.

10 Means are provided to move the spindle 24 upwardly when pressure is removed therefrom, comprising an expansible coil spring 33, surrounding the upper end of the spindle and engaging at its lower end the upper 15 bearing block 31. At its upper end, the spring 33 engages a sleeve 34, rigidly attached to the upper end of the spindle 24. Above the sleeve 34 a head 35 has a swiveled connection with the spindle 24. Rigidly and detachably connected with the lower end of the spindle is a holding element or tool 36 to engage with the valve to rotate the same upon its seat for grinding the valve and seat, as is customary. It is to 20 be understood that any suitable form of tool may be attached to the lower end of the spindle, the invention not being restricted to the precise type of tool shown.

The operation of the apparatus is as follows: By placing the left hand upon the head 35, the operator overcomes the springs 33 and moves the spindle 24 downwardly, whereby the tool 36 is brought into holding engagement with the valve, causing the 30 valve to rotate therewith. The head 35 also aids in steadyng the apparatus, while in operation. The operator holds the handle 21 in the right hand and reciprocates the frame 17'. This causes a reciprocatory movement 35 of the flexible element 22, which being wound about the spool or pulley 23 will cause the same to partake of a reciprocatory-rotary movement, rotating or turning the spindle 24 backward and forward. The movement 40 of the spindle is imparted to the tool 26, which moves the valve in a corresponding manner.

Particular attention is called to the fact that the several parts of the apparatus are 45 readily adjustable, whereby the same may be applied to engines of different sizes and the spindle brought to the proper position with respect to the valve.

It is to be understood that the form of my 50 invention herewith shown and described is to be taken as a preferred example of the same and that various changes in the shape, size, and arrangement of parts may be resorted to without departing from the spirit 55 of the invention or the scope of the subjoined claims.

Having thus described my invention, what I claim is:

1. In a valve grinding apparatus, the com-

bination with a supporting structure, of a 65 longitudinally removable rotatable spindle connected with the supporting structure, yielding means to automatically move the spindle away from the valve, means whereby the spindle may be moved toward the 70 valve, a pulley splined upon the spindle, a reciprocatory frame connected with the supporting structure, and a flexible element connected with the reciprocatory frame and wound about the pulley.

2. In a valve grinding apparatus, the combination with a supporting structure, a longitudinally movable rotatable spindle connected therewith and adapted to carry a 80 valve grinding tool, a pulley connected with the spindle to rotate the same, a movable member connected with the supporting structure and arranged in proximity to the spindle, and a flexible element connected with the movable member and engaging the 85 pulley, substantially as described.

3. In a valve grinding apparatus, the combination with a supporting structure adapted to be attached to the cylinder of an engine, a longitudinally movable rotatable 90 spindle connected with the supporting structure and provided with means whereby the same may be manually moved toward the cylinder, a pulley splined upon the spindle, a reciprocatory frame connected with the 95 supporting structure and arranged near the spindle, a flexible element connected with the reciprocatory frame and engaging the pulley, and a valve engaging tool connected with the inner end of the spindle.

4. In a valve grinding apparatus, a supporting member adapted to be rigidly connected with the cylinder of an engine, a longitudinally movable rotatable spindle arranged near the supporting member, vertically and horizontally adjustable means connecting the spindle and supporting member, a spool splined upon the spindle, a reciprocatory frame arranged near the spool, a 105 flexible element carried by the frame and 110 engaging the spool, vertically and horizontally adjustable means connecting the reciprocatory frame and supporting member, and a valve engaging tool connected with the inner end of the spindle.

5. In a valve grinding apparatus, the combination with a supporting structure, of a longitudinally movable rotatable spindle connected with the supporting structure and adapted to carry a valve grinding tool, yielding means to automatically move the spindle away from the valve, a reciprocatory member connected with the supporting structure, and means whereby the spindle is turned by the reciprocatory movement of 115 the member.

6. In a valve grinding apparatus, a rod having one end screw-threaded to engage

within the spark plug opening of the cylinder, a horizontally adjustable support carried by the rod, a longitudinally movable rotatable spindle connected with the ⁵ port and carrying a valve grinding tool, and means to turn the spindle, substantially as described.

In testimony whereof I affix my signature in presence of two witnesses.

MYRON B. DURGA.
